UNITED STATES PATENT OFFICE.

IGNAZ HUGO PAWLICK, OF SAN FRANCISCO, CALIFORNIA.

BAKING-OVEN.

No. 885,173.

Specification of Letters Patent.

Patented April 21, 1908.

Application filed January 14, 1907. Serial No. 352,070.

To all whom it may concern:

Be it known that I, IGNATZ HUGO PAWLICK, a subject of the Emperor of Germany, and resident of the city and county of San Francisco, State of California, have invented certain new and useful Improvements in Baking-Ovens, of which the following is a specification.

My invention relates to ovens which have 10 a furnace located wholly inside them; and has for its objects, first, to provide improved means for receiving and supporting the loaves in such ovens; second, to provide improved means for readily taking such ovens apart in 15 order to exchange worn out pieces or to move readily from place to place the larger sizes of such ovens.

I attain my objects by means illustrated in the accompanying drawings, of which 20 Figure 1 is a front elevation of my invention; Fig. 2, a top view thereof with the cover removed; Fig. 3 a vertical sectional view taken along the line $x-x$, Fig. 1. Fig. 4 is a perspective view of my improved loaves 25 supporter.

Similar numerals of reference refer to similar parts throughout the drawing and its several views.

My invention consists of a rack 1, Fig. 4, 30 arranged to fit loosely inside a chamber in an outer asbestos lined casing 2, and having a plurality of shelves 3, 4, 5, supported in such position as to register with corresponding closable openings 8, 7, 6, in said outer casing; 35 and of the combinations and arrangements set forth herein.

Describing my rack more particularly, I provide four legs, 9, 10, 11, 12, of angle iron. Between these legs I provide suitable pieces 40 of angle iron extending in parallel planes at various heights, two of which extending from the front legs to the rear I have marked 13, 14, and two, extending along the front, I have marked 15 & 16, it being understood that the 45 corresponding pieces at the rear, front and sides are similarly constructed and attached. Along these pieces I lay blocks of tiling 17, 18, 19, 20, forming floors at various levels. One of these floors 17 forms an upper deck, 50 and another 20 a lower deck. Between these decks I provide a plurality of such floors, three of which are marked at 18, 19, and 21; and these are arranged at such levels as to stand flush with the lower levels of the corresponding closable openings 6, 7, and 8 in the 55 outer casing, when said rack is in position.

Fig. 3 shows the position of said rack, which is inside the chamber inclosed by outer casing 2. The rack is placed in the oven through the open top of the casing 2 when the cover 24 is removed, and by reason of the fact that it does not completely fill the space in the casing, note Fig. 3, and the fact that the frame carrying the shelves passes between the flues 22, 23 Fig. 2, it allows a more 60 perfect circulation of the air in the casing, and also by reason of the fact that the frame is provided with an extra tiled floor below the floor 3 the direct radiation from the firebox is prevented from striking the first shelf 65 on which the material to be baked is placed, thus preventing the burning of the materials in the center of the shelf. Another feature of the removable baking shelves is that they are not secured to the casing 2 in any manner. The rack is simply placed in its place in 70 the casing, the legs resting on the floor freely.

The gaseous products of combustion from the furnace contained inside said chamber are carried by means of lateral pipes 22 and 80 23 to the hollow cover 24 out of which they emerge through stack 25. Flue caps, 26, 27, are provided to facilitate the cleaning of said pipes; and flue caps 28, 29, to facilitate the cleaning of hollow cover 24. Outer casing 2 85 is lined with asbestos, as are the floor of said chamber, and cover 24, in the manner shown. 41 is a damper in stack 25.

Cover 24 rests on top of the lining of casing 2, and is held in position by the outer walls of 90 said casing.

For purposes of repairs, or for knocking down to render the transportation easy, cover 24 is lifted off and rack 1 is drawn out of said chamber. Withdrawing the lines of 95 bolts through flanges shown at 30, 31, in Fig. 1, and the corresponding screws through flanges at the rear, shown at 32, 33, in Fig. 2, separate the parts of outer casing. The doors 35, 36, 37, swing outwardly on hinges 100 38, 39 and 40.

I claim:

In a baking oven, the combination of a casing having doors at the front thereof and an open top, a furnace inside the casing and projecting above the bottom thereof, a flue extending from each side of the furnace to a flue at each side of the casing said latter flues extending upwardly and forwardly and spaced from the casing and shelves, a hollow 105 cover into which the inclined flues extend, an angle iron rack of less superficial area than

the inside of the casing, said rack being free from the casing and provided with a series of shelves and without sides whereby the free circulation of the air from the flues and furnace across the shelves is not impeded, and heat deflecting shelves above and below the baking shelves respectively and carried by the rack.

In testimony whereof I have hereunto signed my name in the presence of two witnesses. 10

IGNAZ HUGO PAWLICK.
